Primary Examiner — Keli L Hill*Assistant Examiner* — Karra S Johnson(74) *Attorney, Agent, or Firm* — Dunlap Bennett & Ludwig PLLC(57) **CLAIM**

The ornamental design for a speaker, as shown and described.

DESCRIPTION

FIG. 1 is a perspective view of a speaker;

FIG. 2 is a front elevated view thereof;

FIG. 3 is a top plan view thereof;

FIG. 4 is a rear elevated view thereof; and,

FIG. 5 is a left side elevated view thereof, the right side being a mirror image thereof.

The broken lines shown in the drawings depict portions of the speaker that form no part of the claimed invention.

1 Claim, 4 Drawing Sheets(56)
